UNITED STATES PATENT OFFICE.

WILLIAM S. LUCKETT, OF EAST ORANGE, NEW JERSEY, ASSIGNOR TO
INTERNATIONAL CIGAR MACHINERY COMPANY, OF NEW YORK, N. Y.,
A CORPORATION OF NEW JERSEY.

FEEDING MECHANISM.

No. 812,219.

Specification of Letters Patent.

Patented Feb. 13, 1906.

Application filed May 28, 1904. Serial No. 210,202.

To all whom it may concern:

Be it known that I, WILLIAM S. LUCKETT, a citizen of the United States, residing at East Orange, county of Essex, and State of New Jersey, have invented certain new and useful Improvements in Feeding Mechanisms, fully described and represented in the following specification and the accompanying drawings, forming a part of the same.

10 This invention relates to certain improvements in feeding mechanisms, the improvements being more particularly intended for use in connection with cigar-machines.

In the manufacture of cigars, and more particularly in the manufacture of that class of cigars which are formed from what are termed "shaped" bunches—that is, bunches which have a greater diameter at the center than at the point and tip—it is desirable to 20 form the bunches from what may be termed "charges" of tobacco, which vary in volume.

The present invention has for its object to produce an improved feeding mechanism primarily intended for use with cigar-machines, although it may be used in other relations by which successive charges varying in volume may be removed from a receiver and delivered, so that a bunch of proper dimensions may be readily formed therefrom.

30 Referring to the accompanying drawings, which illustrate one embodiment of the invention, Figure 1 is a side elevation, partly in section, of so much of a cigar-machine having the improved feeding attachment applied thereto as is necessary to an understanding of the invention. Fig. 2 is a plan view of the construction shown in Fig. 1. Fig. 3 is a view similar to Fig. 2 with the charge-separating means removed. Figs. 4, 5, 6, and 7 40 are detail views.

In the machine which has been selected to illustrate the invention the improved feeding mechanism is shown in connection with a cigar-bunching machine to which the feeding mechanism supplies the material for the bunches. It may be here remarked, however, that the feeding mechanism is capable of use in relations other than the one illustrated.

50 The particular bunch-rolling mechanism illustrated is of the Chianti belt type. It is to be understood, however, that when the improved feeding mechanism is used in con-

nexion with a cigar-bunching mechanism the bunch-rolling mechanism may be of any suitable type. 55

As shown, there is provided a standard 1, which supports the rolling-table 2, over which the rolling-belt 3 rolls the bunch, the belt being secured at one end 4 to the table and at 5 the other end 5 to a bracket forming a part of the standard. The rolling is effected by means of the usual bight-forming roller 6, carried in arms 7, said arms being fast on a shaft 8, mounted in bracket-arms 9, pivoted 65 on a stationary shaft 10. Connected to these arms and extending, in the construction shown, rearwardly therefrom is an operating-lever 11, having a cam-roll 12, said roll engaging with a cam-groove (not shown) in the 70 cam-drum 13. The purpose of this construction, as will be clearly understood by those skilled in the art, is to give the roll a slight vertical movement to enable it to clear the edge of the table 2 as it forms the bight and begins its operating or rolling movement. 75 The swinging of the arms 7, by which the rolling of the bunch is effected, is in the construction shown accomplished by providing the shaft 8 with a segment-arm 14, the segment on said arm being engaged by a segment-arm 15, pivoted on the stationary shaft 10, before referred to, the rear end of said arm being provided with a roll 16, which engages a cam-groove (not shown) in the side of 80 the cam-drum 13, before referred to. After the bunch has been deposited in the loop of the belt the arms are raised slightly and then given a swinging movement to roll the bunch, the bunch being rolled by the traveling loop 90 or bight of the belt in a manner well understood by those familiar with the art.

The parts so far described have no special relation to the invention and are therefore illustrated more or less diagrammatically. 95

The tobacco or other material to be fed by the feeding mechanism to be hereinafter more specifically described is contained in a holder which may be varied widely in its form and construction. In the preferred 100 form of construction, however, the holder will be provided with a plurality of compartments. In the drawings the holder is shown as having three compartments 17, 18, and 19, respectively. As the tobacco is removed 105 from the holder the amount therein is of

course reduced, and means are therefore provided to enable the removing or charge-carrying mechanism to come at the tobacco. While this might be accomplished in various ways, in the preferred construction it will be effected by keeping the tobacco at a constant level in the holder, and in the particular construction shown this is accomplished by providing a movable bottom, which underlies all the compartments in the holder. This bottom, as shown, consists of slats 20, which are secured to an arm 21, mounted to enable the bottom to be moved upward as the amount of tobacco in the holder decreases. The upward movement of the bottom may be secured in any desired way. As shown, the arm 21 carries two spring-pressed pawls 22 and 23. The machine-frame is provided with a standard 24, and this standard carries a fixed rack 25, which is engaged by the pawl 23. Working in this standard 24 and rotated therein is a movable rack 26, this rack being engaged by the pawl 22. The rack 26 is secured at its lower end to a cam-lever 27, said lever being pivoted on a stationary shaft in line with the shaft 10, before referred to, said shaft being shown in dotted lines in Fig. 3 and being marked 10'. This lever 27 is provided at its end with a cam-roll 28, which works in a suitably-formed cam-groove in a drum 29. This drum and the drum 13, before referred to, are mounted on a driving-shaft 30, supported in brackets in the machine-frame.

The mechanism by which the charges of tobacco are removed from the holder may be varied widely in construction. In its preferred form, however, it will embody a charge-carrier provided with suction devices, which are brought into contact with the tobacco and the tobacco being caused to adhere to these devices by the action of the suction. In the construction shown there is provided a head 31, this head being carried on and formed in one piece with a suction-pipe 32, which is elbow-shaped and which communicates with any suitable suction-producing mechanism. (Not shown.) In the preferred form of the construction the mechanism for removing the tobacco from the holder will be of such a character that it removes and transports to the delivery-point different volumes of tobacco or other material being fed. In the construction shown this is effected by providing the head 31 with a plurality of suction-surfaces, and in the construction shown three such surfaces are provided, these surfaces having different areas and being marked 33, 34, and 35. The suction-surface 33 co-operates with the compartment 17, the surface 34 with the compartment 18, and the surface 35 with the compartment 19.

It is obvious that a relative movement must be produced between the mechanism

for removing the tobacco and the holder, and in the construction shown this is accomplished by moving the head and surfaces between the holder and the delivery-point, which in the present instance is the bunch-rolling mechanism, although, as before indicated, the mechanism may, if desired, be used to deliver material in other relations than in a cigar-machine. The particular mechanism by which the head is given its movements may be varied within wide limits. As shown, however, there is provided a vertical shaft 36, said shaft being mounted in suitable bearings in the frame. This shaft extends into a boss or socket 37, depending from the under side of the elbow-pipe 32, the shaft being pinned to the boss or secured in any other desired way. The shaft may be given the movement to swing the head by mechanism which may be of any desired character. As shown, the lower end of the shaft is provided with a segment 38, the said segment being engaged by a segment 39 on a segment-lever 40, said lever being pivoted at 41 to a stud on the frame of the machine. This segment-lever 40 is a bent lever in the construction shown and carries on its end a bowl 42, which runs in a circumferential cam-groove 43, formed in the drum 13, before referred to. In the preferred construction the head after being swung so that its suction-surfaces are over the holder is dropped to bring it into contact with the tobacco or other material in the holder and is then elevated, after which the head is swung to deliver the tobacco. The construction by which the head is given its vertical movement may be of any desired character. As shown, (see Figs. 1, 2, and 3,) there is provided a cam-lever 44, this lever being pivoted on the shaft 10, before referred to, and being provided with a roll 45, which underlies the hub of the segment 38, before referred to. The other end of this lever is provided with a roll 46, which engages a suitably-formed cam-groove in the side of the cam-drum 15, before referred to.

With the construction so far described it is obvious that the suction-head with its suction-surfaces differing in area will be swung over the holder, dropped to pick up the tobacco, and swung back again to the delivery-point, which in the machine shown is the loop of the rolling-belt, and that the surfaces will be brought successively over the delivery-point. It is furthermore obvious that the tobacco will be kept at a proper level in the holder by means of the upwardly-moving bottom before referred to.

The tobacco may be discharged from the surfaces in any desired manner—as, for instance, by cutting off the suction and allowing it to fall therefrom; but in the machine shown the suction will be acting all the time, and devices are therefore provided for posi-

tively removing the tobacco from the suction-surfaces. While these devices may be of any desired character, in the construction shown there is provided a scraper-bar 46, said bar 5 being mounted on a hub 47, which loosely surrounds the boss 37, before referred to, the boss 37 being connected to the hub 47 by means of a torsion-spring 48. The boss 37 is provided with a stop-lug 49, (see Fig. 2,) and 10 the hub 47 is provided with a coöperating stop-lug 50, and the spring 48 normally holds the hub 47 in such a position that its stop-lug 50 will be against the lug 49. It is apparent, therefore, that as the head swings the hub 47 15 will swing with it. A stop 51 is secured to the frame in the path of the bar 46, this stop being so located that the bar 46 will strike it just after the bar has passed the loop in the rolling - belt. (See Fig. 4.) This stop 51 20 checks the further movement of the bar 46, and as the head continues its movement the surfaces 33, 34, and 35 wipe over the bar 46, and the tobacco is removed by it from the surfaces.

25 By providing a holder with a plurality of compartments the tobacco is more readily kept at a proper level to be removed by the removing devices than would be the case if, as might be done, the removing devices operated in connection with a holder having a 30 single compartment. Furthermore, the use of separate compartments enables different qualities or kinds of tobacco to be employed in making a bunch, if it is desired. It will also 35 be understood that by properly proportioning the area of the different removing-surfaces the shape of the bunch may be readily controlled, the different surfaces depositing the tobacco in the apron or other receiving 40 device at the points where it is wanted to properly shape the bunch.

The operation of the machine will be fully understood from the preceding description, and a detailed statement is therefore unnecessary.

45 Changes and variations may be made in the construction by which this invention is carried into effect. The invention is not, therefore, to be confined to the particular 50 construction herein shown and described.

What is claimed is—

1. The combination with a holder, of means for removing a plurality of individual charges and conveying them separately to and assembling them at a common delivery-point, and a rolling mechanism, substantially as described.

2. The combination with a holder, of means for removing a plurality of individual charges 55 of varying volume therefrom and conveying them separately to and assembling them at a common delivery-point, and a rolling mechanism, substantially as described.

3. The combination with a rolling mechanism, of a holder, means for removing a plu-

rality of individual charges from the holder and transferring the charges separately to and assembling them in the rolling mechanism, substantially as described.

4. The combination with a holder having a plurality of compartments, of means for removing individual charges from the compartments and transferring them to and assembling them at a common delivery-point, and a rolling mechanism, substantially as described.

5. The combination with a rolling mechanism, of a holder, a charge-carrier adapted to carry a plurality of charges, means for moving the charge-carrier between the holder and the rolling mechanism, and means for causing the carrier to deliver the charges successively to the rolling mechanism, substantially as described.

6. The combination with a rolling mechanism, of a holder, a charge-carrier adapted to carry a plurality of charges of varying volume, means for moving the charge-carrier between the holder and the rolling mechanism, and means for causing the carrier to deliver the charges successively to the rolling mechanism, substantially as described.

7. The combination with a rolling mechanism, of a holder having a plurality of compartments, means for removing a charge from each compartment and for transferring the charges separately to and assembling them in the rolling mechanism, substantially as described.

8. The combination with a holder comprising a plurality of compartments, of means for removing individual charges from the holder and transporting them separately to and assembling them at a common delivery-point, substantially as described.

9. The combination with a holder, of a suction charge-separator operating to remove a plurality of individual charges from the holder and transport them to a common delivery-point, substantially as described.

10. The combination with a holder, of a suction charge-separator operating to remove a plurality of individual charges varying in volume from the holder and transport them to a common delivery-point, substantially as described.

11. The combination with a rolling mechanism, of a holder for granular material, a suction charge-separator operating to remove a plurality of charges from the holder, and means for actuating the separator to transfer the charges to the rolling mechanism, substantially as described.

12. The combination with a rolling mechanism, of a holder, a suction charge-separator operating to remove a plurality of charges varying in volume from the holder, and means for actuating the separator to transfer the charges to the rolling mechanism, substantially as described.

13. The combination with a holder for granular material, of suction charge-removing means, means for effecting relative movements between the holder and the removing means, whereby the removing means is positioned with respect to the material in the holder, and means whereby the material in the holder and the removing means are brought into juxtaposition. 5
14. The combination with a rolling mechanism, of a holder for granular material, suction charge-removing means, and means for moving the charge-removing means into taking position with respect to the holder and delivery position with respect to the rolling mechanism, and means whereby the material in the holder and the removing means are brought into juxtaposition. 10
15. The combination with a rolling mechanism, of a holder for granular material, a suction charge-removing device, and means for causing said device to remove charges from the holder and transfer them to the rolling mechanism, substantially as described. 20
16. The combination with a holder comprising a plurality of compartments, of charge-removing means coöperating with each compartment, and means for actuating said charge-removing means to remove charges from the compartments and to assemble them at a common delivery-point, said charge-removing means being constructed to remove charges of varying volume from different compartments, substantially as described. 25
17. The combination with a rolling mechanism, of a holder comprising a plurality of compartments, suction charge-removing means coöperating with each compartment, and mechanism for actuating said charge-removing means to remove charges from the compartments and deliver them to the rolling mechanism, substantially as described. 30
18. The combination with a rolling mechanism, of a holder comprising a plurality of compartments, suction charge-removing means coöperating with each compartment, said charge-removing means being constructed to remove charges of different volumes from different compartments, and means for actuating said charge-removing means to deliver the charges to the rolling mechanism, substantially as described. 40
19. The combination with a holder, of a suction charge-carrier having a plurality of operating-faces varying in area, means for producing a relative movement between the charge-carrier and the holder and for causing the faces to deliver at a common point, substantially as described. 50
20. The combination with a holder having a plurality of compartments, of a suction charge-carrier having a plurality of operating-surfaces, one for each compartment, said surfaces differing in area, and means for moving the carrier to bring its surfaces to a common discharging-point, substantially as described. 55
21. The combination with a rolling mechanism, of a holder having a plurality of compartments, a suction-carrier having a plurality of operating-surfaces varying in area, and means for moving the carrier so as to bring the surfaces of the carrier into discharging position with respect to the rolling mechanism, substantially as described. 70
22. The combination with a rolling mechanism, of a holder having a plurality of compartments, means for maintaining the material at a substantially constant level in the compartments, a suction-head having a plurality of operating-surfaces, one for each compartment, the surfaces varying in area, and means for moving the head from the holder to the rolling mechanism, substantially as described. 80
23. The combination with a rolling mechanism, of a holder having a plurality of compartments, a suction-head having a plurality of operating-surfaces differing in area, means for moving the head from the holder to the rolling mechanism, and a discharging device coöperating with the surfaces, substantially as described. 85
24. The combination with a rolling mechanism, of a holder having a plurality of compartments, a suction-head having a plurality of operating-surfaces differing in area, means for moving the head from the holder to the rolling mechanism, and a scraper coöperating with the surfaces, substantially as described. 90
25. The combination with a rolling mechanism, of a holder having a plurality of compartments, means for maintaining the material at a substantially constant level in the compartments, a suction-head having a plurality of operating-surfaces, one for each compartment, the surfaces varying in area, means for moving the head from the holder to the rolling mechanism, and a discharging device coöperating with the surfaces, substantially as described. 95
26. The combination with a rolling mechanism, of a holder having a plurality of compartments, means for maintaining the material at a substantially constant level in the compartments, a suction-head having a plurality of operating-surfaces, one for each compartment, the surfaces varying in area, means for moving the head from the holder to the rolling mechanism, and a scraper coöperating with the surfaces, substantially as described. 100
